UNITED STATES PATENT OFFICE.

LAURENCE M. COCKADAY, OF NEW YORK, N. Y.

RADIOTELEGRAPHY.

1,299,823.

Specification of Letters Patent.

Patented Apr. 8, 1919.

Application filed October 27, 1917. Serial No. 198,805.

To all whom it may concern:

Be it known that I, LAURENCE M. COCKADAY, a citizen of the United States, and a resident of the borough of Manhattan, in the city of New York, county and State of New York, have invented certain new and useful Improvements in and Relating to Radiotelegraphy, of which the following is a specification.

10 The invention relates to radiotelegraphy and it particularly relates to an apparatus and method whereby there can be produced high potential electrical oscillations from a direct current or other supply.

15 According to my invention there are three circuits employed: the power circuit, the closed circuit and the aerial circuit. The current source of energy (preferably direct current) is made and broken by an interrupter hereinafter described which controls the frequency of the applied current in the power circuit, thereby inducing in the closed circuit a series of high potential impacts which are uniformly spaced and separately stored up until discharged through a timing spark-gap device which controls the time of discharge of said impacts and as a result of these discharges energizing by induction the aerial circuit with a series of groups of high potential high frequency oscillations of decaying amplitude and causing wave trains to be emitted from the aerial in the form of Hertzian waves.

The construction just referred to employs a step-up transformer referred to as an initial step-up transformer and also a second transformer referred to as the oscillation transformer. The primary coil of the initial step-up transformer is in the power circuit; the secondary coil of the initial step-up transformer and the primary coil of the spark-gap device are in the closed circuit; and the secondary coil of the oscillation transformer as well as the aerial are in the aerial circuit.

As herein illustrated and described the invention, in its preferred form, is directed to a construction in which the sparking is established and interrupted at a time when

no current is being supplied to the primary coil of the initial transformer. In this form of apparatus a condenser is an important element and is connected in the closed circuit and serves to store the energy until discharged by the sparking. The invention, however, is not limited to a construction in which the sparking takes place at such a time for it comprehends or includes a construction in which the sparking may take place at a time when the current is being supplied to the primary coil of the initial step-up transformer—in other words, at a time when the condenser and the secondary coil to which the condenser is connected has an induced electrical current passing to or through it. Such a construction is also illustrated.

In the latter construction it might be possible to eliminate the condenser or make it small, but the resulting Hertzian waves would not be so powerful as in the preferred form of apparatus.

In the construction of an apparatus for performing the invention it is desirable that the impulses finally received by the primary of the oscillation transformer be in the form of damped sets of high potential oscillations of high frequency and also that the interrupter employed in the power circuit should operate without arcing on breaking the current, and according to my invention there is provided a means for accomplishing these ends.

In the preferred form of apparatus the interrupter and the timing spark-gap device are so constructed that when the interrupter is completing the power circuit the timing spark-gap device is out of sparking position, no discharge taking place in the spark-gap until the interrupter has broken the power circuit. During the time when the power circuit is broken the timing spark-gap device moves into sparking position and out of said position, and the same cycle of operations is successively repeated. From this it will be seen that the condenser which is included in the closed circuit is charged and discharged alternately, the function of

charge being governed by the interrupter in the power circuit and the function of discharge being governed by the timing spark-gap device in the closed circuit, the operation of charging the condenser by the power circuit current and the discharging of the condenser occurring in different periods of time.

The invention relates to the features above referred to as well as to others which will appear in the course of the following description and in the accompanying claims.

As illustrating certain specific embodiments of the invention reference is made to the drawings forming a part of this specification, in which drawings,

Fig. 1 is a diagrammatic view illustrating the essential elements of a radiotelegraph apparatus constructed for performing the invention. In this figure a preferred form of apparatus is illustrated.

Fig. 2 is a side elevational view of a combined switch and spark-gap device; viz., of a combined interrupter and timing spark-gap device.

Fig. 3 is a vertical sectional view of the combined interrupter and timing spark-gap device shown in Fig. 2.

Fig. 4 is a vertical sectional view of the spark-gap portion of said device and is a view taken as on the line 4-4 of Fig. 3, looking in the direction of the arrows.

Fig. 5 is a view taken as on the plane indicated by the line 5-5 of Fig. 2 looking in the direction of the arrows. In this figure there is shown a portion of the switch mechanism of the combined switch and spark-gap device.

Fig. 6 is a view taken as on the plane indicated by the line 6-6 of Fig. 5, looking in the direction of the arrows.

Fig. 7 is a diagrammatic view of radiotelegraph apparatus which is comprehended or included within my invention. In this form of apparatus the sparking through the timing spark-gap device may take place when current is being supplied from the power circuit due to the switch of said circuit being closed.

50 A source of current supply, preferably a direct current of constant potential, is designated by E and this is included in a power circuit PC which comprises line 2, primary coil 3 of an initial step-up transformer IT, lines 4, 5, 6 and 7, stationary contact c^1 , movable contact c^2 , stationary contact c^3 of a switch C, lines 8, 9, 10 and 11, key K, line 12 and hand switch H.

In the construction shown the contact c^2 is any one of a number of such contacts that are uniformly spaced and insulated from each other and that are carried on a rotary disk D that preferably provides the insulating material for separating the contacts c^2 . The switch C which includes the

stationary contacts c^1 and c^3 and the movable contacts on the disk D of insulating material provides the interrupter which was previously referred to and which is herein-after described more in detail. The secondary coil of the initial step-up transformer IT is designated by 13 and this is comprised in a closed or oscillating circuit OC that includes lines 14, 15, 16 and 17, primary coil 18 of the oscillation transformer OT, lines 19, 20, 21 and 22, stationary terminal member g^1 , rotary bridge member g^2 , stationary terminal g^3 , lines 23, 24 and 25.

The terminal member g^1 , rotary bridge g^2 and terminal member g^3 may be considered to constitute the essential members of the rotary spark-gap device SG. This rotary spark-gap device constitutes the timing spark-gap that was previously referred to and which is herein-after described more in detail. The secondary coil of the oscillation transformer OT is designated by the reference character 26 and is included in an open or aerial circuit. One terminal of this secondary coil 26 is shown as being connected by lines 27 and 28 to an aerial A. The function of an aerial is well known in the art and may be described as an aerial member, or members, for receiving or transmitting electrical energy and particularly in wireless telegraphy work.

The other terminal of the secondary coil 26 of the oscillation transformer is shown as being connected through the line 29, ammeter M and line 30 to switch s so that said secondary coil 26 can be connected to ground G or to a second aerial or counterpoised aerial AA, as it is frequently referred to in the art. The hand switch H above referred to can be relied upon to close the direct current circuit, viz., the power circuit, when it is desired to use the apparatus and to open said circuit when the apparatus is not in use. The key K indicated in said circuit can be utilized to transmit messages by means of a telegraphic code. A condenser X connected by lines 31 and 32 is shunted across the terminals of the switch C. A condenser Y is shunted across the terminals of the secondary coil of the initial transformer by means of lines 33 and 34.

In the diagrammatic view shown in Fig. 1 it will be observed that there are a number of equally spaced movable contact members c^2 which are secured to the face of the wheel or disk D. This wheel or disk D may be referred to as a rotary contact carrying member since it is mounted upon and secured to the rotating shaft S and carries the spaced contacts c^2 just referred to. There is also mounted upon this shaft S and secured thereto the rotary bridge member g^2 of the spark-gap device SG and this bridge member g^2 has a number of equally spaced terminal members g^1 arranged in pairs so that

when any one of the spaced terminal members g^t is opposite the stationary terminal g^1 another of the spaced terminal members g^t will be opposite the other stationary terminal member g^3 .

In the construction shown with the rotary bridge member directly connected to the wheel or disk D, whereby both of said members make the same revolutions per minute, 10 then in that case there is exactly the same number of teeth or terminals g^t upon the rotary bridge member g^2 as there are contacts c^2 upon the wheel or disk D. The arrangement is also such that each time a contact c^2 completes the closing of the switch C then the terminals g^t are in such position 15 relative to the stationary terminals g^1 and g^3 that no sparking can take place; or, in other words, each time the power circuit PC is 20 closed by the switch C the members of the spark-gap device SG are in such a position that no sparking can take place in the closed circuit OC, the condenser Y receiving the charge and holding it until the 25 power circuit is broken on account of rotation of members being mounted on shaft, which same rotation will afterward bring the spark-gap into a position whereby the condenser can discharge its energy across 30 the gap. The device which comprises the shaft S, the members of the spark-gap device SG and the members of the switch C may be considered as a combined switch 35 and spark-gap device, and this is properly referred to as a device comprising a combined interrupter and timing spark-gap since the switch serves as an interrupter and the rotary bridge member, which is connected to the switch, serves to time the 40 sparking that takes place in the spark-gap device.

One form of such device is shown in Figs. 2 to 6. In said figures the casing of the device is designated by B and it comprises 45 the upper and lower halves b and b^1 which are held in assembled position in any suitable manner as by means of bolts 35. The shaft shown in these figures is designated by S and corresponds in its function to the shaft S shown in Fig. 1. This shaft may 50 be driven as by a motor indicated diagrammatically at P. It will be observed that the casing is divided into two compartments, 36 and 37, by the partition 38. Upon the 55 shaft S the disk D heretofore referred to is mounted and secured in place by means of a screw 39, as shown in Fig. 3. The electrical bridging element of the rotary bridge member g^2 is in the form of a metal ring 40 having the equally spaced terminals g^t thereupon and this ring 40 is held in place by 60 means of screws 41 on a body of insulating material 42. This body of insulating material 42 is in the form of a rotary carrier 65 which is held in place on the shaft S by,

means of a screw 43. The stationary terminals g^1 and g^3 are held in place in the casing B by means of holders 44 and screws 45. The holders 44 are of insulating material whereby the terminals g^1 and g^3 are 70 each insulated from the casing. From what has been stated in previous portions of this specification it will be clear that the switch C is closed each time a movable contact c^2 75 engages the stationary contacts c^1 and c^3 , 80 said contacts c^1 and c^3 being clearly shown in Figs. 5 and 6. Each of the movable contacts c^2 is secured in place on the wheel or disk by means of a screw 46. The wheel or disk D is of course made of insulating material. The stationary contacts c^1 and c^2 are preferably forced continuously against the contact carrying member or wheel D by means of springs 47 and 48 which are 85 respectively in the sockets 49 and 50. These sockets are insulated from the casing in which they are located in any suitable manner, as by means of insulating material at 51 and 52 respectively.

It will be observed that the width or peripheral dimension x of the contacts c^2 is less than the peripheral distance y between adjacent contacts and as above stated it will also be observed that the contacts c^2 are 90 equally spaced about the periphery of the 95 wheel or disk D which is constructed in such a manner that the several contacts c^2 are insulated from each other. As the motor P rotates the wheel the circuit is successively closed and opened at the switch C by 100 the contacts c^2 each successively moving into and out of engagement with the stationary contacts c^1 and c^3 . The motor P rotates so that the switch C is broken, for example, 105 500 times per second and this results in 500 cycles per second in the system. This number of cycles is of high frequency and any device which has 400 cycles per second or more comes within the term "high frequency" as employed in this specification. 110

The spark frequency which is a function of the number of discharges bridging the gap per second can be readily changed in the system herein shown and described by changing the speed of the motor which operates the shaft S and consequently any desired frequency can be obtained by a proper regulation of the speed of rotation of this shaft. Therefore, according to the system herein described an electric current 120 can be converted into a series of impacts or pulsations which induce a series of oscillations in a closed or oscillating circuit and which, on being discharged through the rotary spark-gap in turn induce a wave train 125 in an open circuit in which there is included an aerial. This wave train has a low decrement or is a pure wave and there is no reaction from the open circuit back upon said closed or oscillating circuit and this applies 130

no matter what is the wave length that is employed in said open circuit.

In the apparatus which I have constructed I have employed a 500 cycle one kilowatt 5 transformer for the initial transformer and this I have supplied with current having a voltage of 110-125.

According to my system the charge held by the condenser is discharged and damped 10 outright on account of the rotary spark-gap moving into and out of position during an infinitesimal part of a second. This damping is also facilitated by placing gaps in air-tight chambers and is of importance in 15 this type of apparatus as it makes a very short group of oscillations each time discharge occurs in a closed circuit and these groups are damped out before reaction from the secondary coil of the oscillation trans- 20 former can take place, thus resulting in a wave train of exceedingly low decrement in the open or antenna circuit regardless of the wave length of said circuit.

Another advantage of this system is that 25 the condenser Y—the high potential condenser that is shunted across the lines of the secondary coil of the step-up initial transformer IT—can be made of very small capacity on account of the instantaneous 30 high potential current induced in said secondary coil. Due to the fact that the power circuit is closed only for a short time it is necessary to use at the most only a small condenser to shunt the contacts of the switch 35 C. It will therefore be seen that according to my system there is an advantage in over-coming the necessity of using large condensers in the power circuit. The employ- 40 ment of a small condenser, however, in the closed circuit makes it possible to work the system on very short wave lengths.

The electrical energy employed in the apparatus and which is supplied to the power circuit is preferably that received from a 45 direct current generator, but it might be derived from a storage battery, or possibly even from an alternating current generator, but the results from the latter would not be as satisfactory as with the direct current 50 generator or battery.

The detailed description previously given particularly applies to the construction illustrated in Fig. 1. According to the construction of said figure the sparking through the 55 timing spark-gap device takes place only when the current in the power circuit is interrupted. In Fig. 7 it will be observed that the timing spark-gap is arranged so that sparking takes place when the current 60 is being supplied through the power circuit, this because the terminals g^4 of the rotary spark-gap member are adjacent to the stationary terminals g^1, g^2 when a movable contact c^2 engages the stationary contacts c^1, c^3 . 65 Such a condition can be readily obtained by

the screw 43 or screw 39 either of which permits an insulation carrier (as 42 or D) to be positioned on the shaft S so as to attain the desired end. As previously stated applicant considers his invention as comprehending or including the construction illustrated in said Fig. 7.

The improvements herein set forth are not limited to the precise construction and arrangement shown and described for they 75 may be embodied in various forms and modifications without departing from the spirit and scope of the invention.

What I claim is:

1. In high frequency apparatus having a 80 main supply circuit, the combination of a rotary make and break device controlling said circuit and a rotary spark gap co-operating with said make and break device and rotating in synchronism therewith, said 85 make and break device and spark gap being adjustable relatively to each other to vary the functioning of the spark gap relatively to the make and break device as may be desired.

2. In an apparatus for producing high frequency electrical impulses, the combination of a primary and secondary circuit, an interrupter in the primary circuit, and a spark gap in the secondary circuit synchronously and adjustably co-operating there- 95 with.

3. The method of producing high frequency electrical impulses, comprising positively interrupting a primary supply of 100 energy, and synchronously and selectively discharging an induced secondary high frequency oscillation.

4. The method of producing high frequency electrical impulses, comprising positively interrupting a primary supply of 105 energy and selectively discharging an induced secondary high frequency oscillation.

5. In radiotelegraphy, an apparatus comprising in combination a power circuit having therein the primary coil of an initial step-up transformer, an oscillating circuit having therein the secondary coil of said initial transformer, a condenser and the primary coil of an oscillation transformer, 110 said apparatus comprising a rotary make and break device for successively making and breaking the power circuit, and a rotary spark gap device in the oscillating circuit rotating in synchronism with said make and break device.

6. In radiotelegraphy, an apparatus comprising in combination a direct current power circuit having therein the primary coil of an initial step-up transformer, an 125 oscillating circuit having therein the secondary coil of said transformer, a condenser and the primary coil of an oscillation transformer, said apparatus comprising a rotary make and break device for successively mak- 130

ing and breaking the power circuit, and a rotary spark gap device coöperating with said make and break device and rotating in synchronism therewith.

5 7. In an apparatus for producing high frequency electrical impulses, the combination of a primary and a secondary circuit, an interrupter in the primary circuit, and

a synchronously operated spark gap in the secondary circuit.

This specification signed and witnessed this 26th day of October, A. D. 1917.
